UNITED STATES PATENT OFFICE.

DAVID L. CRAWFORD, OF OAKMONT, PENNSYLVANIA, ASSIGNOR TO VERONA TOOL WORKS, OF PITTSBURGH, PENNSYLVANIA, A CORPORATION OF PENNSYLVANIA.

RAIL BOND.

Application filed April 7, 1926. Serial No. 100,314.

The present invention relates broadly to the art of railways, and more particularly to bonds adaptable for use therewith for establishing an effective connection for the transmission of electric current between adjacent rail ends.

It has heretofore been proposed in the art to which the present invention relates to provide rail bonds of resilient material, such as 10 spring steel, adapted to be clamped in position between the webs of the rail ends to be bonded and the fish plates or splice bars ordinarily utilized for completing the joints. Such bonds have not infrequently comprised 15 a body of suitable material curved both longitudinally and transversely throughout the length and width thereof.

In actual practice, I have found that while the transverse curvature provides effective 20 rail engaging points and the longitudinal curvature imparts the desired resiliency, the combination of such curves is objectionable from a practical standpoint for the reason that the transverse curvature not only limits 25 the area of contact between the bond and fish plate or splice bar, but also tends to impose localized strains on the bond, not infrequently resulting in fracture thereof.

It is one of the objects of the present invention to provide a rail bond having effective rail engaging points, but obviating the objections involved in the use of the limited area of contact with the fish plates or splice bars. This is preferably accomplished by so 35 constructing the bond as to provide a substantially flat intermediate portion for cooperation with the fish plate which bears against the bond, and serving not only to more effectively distribute the strains 40 throughout the body of the bond, but to considerably decrease the permanent set which has heretofore resulted from a clamping action to which the bonds are subjected.

In the accompanying drawings there is 45 shown, for purposes of illustration only, a preferred embodiment of the present invention, it being understood that the drawings do not define the limits of my invention as changes in the construction disclosed therein, as well as its manner of use, may be made 50 without departing either from the spirit of the invention or the scope of my broader claims.

In the drawings,
55 Fig. 1 is a sectional view through a por-

tion of a rail joint showing my improved track bond in position;

Fig. 2 is a side elevational view of the construction illustrated in Fig. 1, one of the fish plates being removed for the sake of clearness and the clamping bolts being shown in section;

Fig. 3 is a perspective view of the bond;

Fig. 4 is a longitudinal sectional view through the bond at substantially the center 65 portion thereof; and

Fig. 5 is a transverse sectional view on the line V—V of Fig. 4, looking in the direction of the arrows.

With reference more particularly to Figs. 70 1 and 2 of the drawings, there is shown a portion of a track joint, the drawings indicating adjacent rail sections 2 and 3 having the joint between them bridged in well-known manner by fish plates or splice bars 4.

Between the center bolts 5, provided for holding the fish plates in position, there is sufficient room in all standard joints with which I am familiar to permit the insertion 80 of a bond embodying the features of the present invention, irrespective of whether the actual distance between the centers of these bolts is long or short. In the drawings there is actually indicated a bond 6 intermediate these bolts, the bond comprising a relatively 85 long and narrow strip of suitable material, such as spring steel, the edge portions 7 of which are substantially uniformly and continuously longitudinally curved as shown in Fig. 3.

The end portions 8 of the bond are curved transversely to provide inwardly directed points 9 adapted to effectively engage the webs of the adjacent rails in such manner as to penetrate rust or other material thereon, 95 and thereby establish the desired electrical contact. The intermediate portion of the bond is shaped to provide a substantially flat zone 10 of considerable area, this zone providing a comparatively large area of contact 100 between one of the fish plates and the bond, as clearly indicated in Fig. 1 of the drawings. By reason of this zone, the existence of highly localized strains in the bond, due to tightening of the nuts 11, is prevented, and the strains 105 distributed throughout substantially the entire area of the bond.

It will also be apparent to those skilled in the art that a bond constructed as disclosed herein has a less overall height than bonds 110

which are uniformly curved both transversely and longitudinally throughout the entire length. The bond may, therefore, initially be used with joints in which there is a minimum space between the insides of the splice bars and the adjacent faces of the rail webs. Due to this construction, the insertion of the bond is facilitated. Furthermore, when compression becomes effective on the bond, the compression is initially effective over a considerable area as compared to a comparatively small well localized area, thereby enabling the desired bonding action to be more quickly obtained without straining any portion of the bond to such an extent as to result in fracture thereof. This constitutes one of the advantages of the present invention.

A further advantage of the invention arises from the provision of a bond having both a longitudinal and transverse curvature in its end portions with a substantially flat intermediate portion whereby the permanent set taken by the bond is reduced to a minimum.

I claim:—

25 1. As an article of manufacture, a rail bond comprising a body of spring material having

a central portion substantially flat in both transverse and longitudinal section, which provides a relatively long and broad bearing surface for engagement with one element, and having arcuate shaped end portions, to form relatively sharp corners for engagement with another element.

2. As an article of manufacture, a rail bond having a relatively long and wide substantially flat intermediate zone for an engagement with a surface of an element to be bonded, and having transversely curved ends, to provide four relatively sharp corners for engagement with surfaces of other elements to be bonded.

3. As an article of manufacture, a rail bond having end portions curved transversely and longitudinally, to provide four relatively sharp corners for engagement with surfaces of elements to be bonded, and connected by an intermediate relatively long and wide substantially flat portion, for engagement with a surface of another element to be bonded.

In testimony whereof I have hereunto set my hand.

DAVID L. CRAWFORD.
